PORTABLE GRAIN CLEANING MACHINE

John W. Hoefling, Chico, Calif.

Application May 29, 1930. Serial No. 457,376

4 Claims. (Cl. 209—12)

This invention relates to the treatment of grain and has special reference to a portable grain cleaning machine.

In the close cleaning of grain, as for seed purposes, it is desirable to use an assembly of aspirators, screening mechanisms and disc separators to effect complete separation of the good grain from that which is undesirable and from foreign seeds and materials. It is also desirable to provide in such a combination a smut treating device and a supply bin for maintaining a constant feed, together with means for conveying the grain from one to another of the mechanisms successively, thus doing a complete job of cleaning and also of smut treating in one handling. It is further desirable that such a combination be capable of handling any of the common grains, that the various mechanisms may be used either singly or in combination, and that the whole be portably and compactly mounted for quick moving from place to place without loss of time for knocking down and setting up.

One important object of the present invention is to provide an improved and novel compact arrangement of the various mechanisms desirable in such a grain cleaner; the arrangement being such that the entire may be mounted on a motor truck frame of the usual length; that the truck motor provide the power for operating as well as transporting; that the various mechanisms be driven simply one from the other without necessity for a countershaft; that such of the mechanisms as are not required for certain types of work may be idle while the necessary ones only are in motion; that changes in adjustment for different grains may be made instantly; that the functions of the various units be in full view of the operator; that all parts may be quickly and thoroughly cleaned out after operation; that all of the various separations made be conveniently spouted to separate sacks; that the grain enters and discharges side by side at the rear for efficient handling; that after treating for smut the excess powder be removed from the grain; that effective control of the poisonous dust be provided at the sacking spouts; that the whole mechanical structure may conveniently be removed from the truck chassis to release the truck for other service if desired; that the said structure may be removed from the chassis mounted otherwise (as for instance stationarily).

Furthermore, it has been customary in the suction-and-screen types of machines for this purpose, to place the eccentric shaft (used for obtaining reciprocation of the screens) at one end of

the machine exterior of the main frame. This shaft is usually placed at the forward end. In this position it not only adds considerably to the length of the machine but also requires a separate belt to drive it and a countershaft is necessary for power transmission to the rear units of the machine.

A second important object of the invention is to improve the construction of machines for this purpose by arranging the eccentric above mentioned, in a position intermediate of the length of the screens and preferably between them, through clearance holes cut to receive said shaft. This new arrangement of the eccentric shaft reduces the overall length of the machine, puts it entirely out of the way, allows it to be driven by the same belt that drives the fan shaft above, and provides a countershaft for driving the rear parts of the whole machine.

With the above objects in view, the invention consists in general of certain novel details of construction and arrangements and combinations of parts hereinafter fully described, illustrated in the accompanying drawings and specifically claimed.

In the accompanying drawings, like characters of reference indicate like parts in the several views, and:

Figure 1 is a right side elevation of the improved machine;

Figure 2 is a left side elevation;

Figure 3 is a detail elevation showing the manner of mounting the eccentric shaft in the improved location;

Figure 4 is a detail elevation showing the manner of connecting the eccentric shaft and screens; and

Figure 5 is a rear elevation of the machine.

In the embodiment of the invention here disclosed there will be seen a motor truck chassis of ordinary standard type and size and having the special driver's cab II which is open at the rear. Mounted directly back of the cab on the chassis and with its receiving end forward is a specially adapted conventional type suction and screen grain separator. This separator occupies the entire space rearwardly as far as the vertically proportioned accumulator bin 61. This bin 61

rests on the chassis frame and extends upwardly as far as the conveyor casing 38. Immediately to the rear of the bin 61 is the conventional disc grain separator 59 mounted on the chassis frame

with the smut treating machine 57 directly above it, and the elevators 34 bringing up the rear. The detail construction of these main units and

others of the mechanisms employed is not shown here as the present invention has no relation to the specific characters of the mechanisms used but relates instead to the arrangement and co-relation of such or similar mechanisms, to accomplish the objects previously set forth.

The mechanical operation of the machine is accomplished by power derived from the truck motor through a power take-off (not shown) actuating shaft 14, which is connected by bevel gearing 13 to the shaft 12 which is suitably journaled and extends across the chassis just forward of the rear truck wheels. A belt 31 runs around pulleys 28, 29 and 30 to drive suction fans 27 and eccentric shaft 20, an idler pulley 32 being provided to secure proper engagement of the belt with pulleys 29 and 30. The other pulleys, belts, sprockets and chains in immediate relation thereto perform the various familiar functions associated with the suction and screen type of separator.

The eccentric shaft 20 in its new location as shown here extends across the machine between the screens and is located adjacent the rear posts 16. This shaft is supported in suitable bearings, that on the left of machine being best shown in Figure 3 where it will be seen that the bearing 21 is mounted on a pair of vertically spaced blocks 22 resting against the forward side of the post 16 so that the bearing while supported from said post is spaced forwardly therefrom the space between the bearing and the post and between the blocks 22 being sufficient to permit passage of the tailings spout 23 leading from the upper screen 18. On the shaft 20 are located the usual eccentrics 24 connected by blades 25 to the screens to impart to them the required reciprocating motion.

In Figure 2 the belt 50 running over pulleys 49 and 51 drives the three elevators 34 which have one common head shaft 52, the shaft 52 in turn through sprockets 62 and 63 and chain 64 (Figure 1) driving the drag block conveyor in casing 38. In Figure 2 again, the eccentric shaft 20, through belt 54 over pulleys 55 and 56 drives the disc separator 59. The smut treatment dust collecting fan 66 is driven from the right end of shaft 65 through pulleys 67 and 68, while the smut treating machine 57 is driven also from shaft 65 by a chain and sprockets 69, Figure 1. The treating powder metering device enclosed in the box 70 is actuated by the vertical shaft 71 from a bevel gear arrangement at 72.

In operation the grain is introduced through the hopper 36 at the rear of the machine, is elevated by the middle elevator into the conveyor 38 which carries it forward to the feed controlling hopper 39 of the screen and suction machine. The surplus grain (over the desired output as regulated at this point) is carried back by the same conveyor 38 to the reserve bin 61 where it accumulates until the hopper 36 runs empty, whereupon it automatically flows into the hopper 36 again to maintain a constant supply to hopper 39 at all times. (The arrangement and operation of this reserve system is more fully disclosed in my co-pending Patent No. 1,809,701.)

In passing through the suction and screen machine all light material and all that smaller or larger in diameter than the grain is removed from the grain which is then discharged at point 73 (Figure 4) onto the grain pan 74 which is in constant reciprocating motion through fixed attachment to the lower screen shoe. The grain

pan 74 in turn discharges into the left hand elevator boot for re-elevation and discharges again through spout 76 into the disc separator 59 where separations by length of kernel are made. The thoroughly cleaned grain leaves the disc separator at either opening 77 or 78, depending on the kind of grain being handled, enters right hand elevator boot through conduit 60 and is elevated into smut-treating machine 57 by way of spout 79. Spout 79 is recessed to receive the treating powder container 70 from which the powder is metered into the passing stream of grain. The treated grain discharges from treating machine 57 over a screen surface in conduit 80 for removal of loose powder, to the sacking spouts 37. Suction fan 66 is connected by pipe 81 to sacking spouts 37 to draw off floating dust, discharging it upwardly away from the operators through pipe 82.

Grain may be run through the suction and screen separator alone by means of gate 83 in spout 76 (Figure 2), the belt 54 being removed also to allow the disc separator and the smut treating machine to remain inactive. The gate 83 then turns the grain stream at this point directly into the discharging conduit, 80.

It is obvious that many changes may be made in the invention without departing from the material details thereof. It is not therefore desired to confine the invention to the exact form herein described, but it is wished to include all such as come within the scope claimed.

Having thus described the invention, what is claimed is:—

1. In a portable grain cleaner, a supporting chassis, a suction screen machine including longitudinally extending aspirating and screening mechanism positioned forwardly on said chassis, a grain hopper at the rear end of the machine, an elevator and a conveyor arranged to receive grain from the hopper and convey it up and over the suction screen machine onto the aspirating and screening mechanism, a grain bin at the rear of the suction screen machine to receive the aspirated and screened grain, a second elevator in communication with the grain bin, a disk grain separator in communication with the second elevator, a third elevator receiving grain from the separator, a smut treating machine in communication with the third elevator, means to drive the screens, separator, elevators and smut treating machine, the elevators being spaced laterally across the rear of the supporting chassis, the grain hopper being located between the middle elevator and the elevator at one side and a sacking device between the middle elevator and the elevator at the other side.

2. In a portable grain cleaner, a supporting chassis, a suction screen machine including longitudinally extending aspirating and screening mechanism positioned forwardly on said chassis, an elevator and a conveyor arranged to receive grain at the rear of the machine and convey it up and over the suction screen machine to deliver the grain at the front end of the machine onto the aspirating and screening mechanism, a second elevator receiving grain from the suction screen machine, a disk grain separator in communication with the second elevator, a smut treating machine above said disk separator, a third elevator receiving grain from the disk grain separator for delivery to the smut treating machine, driving means for the several mechanisms, said elevators being spaced laterally across the

- rear of the supporting chassis, a receiving hopper between the middle elevator and the elevator at one side and a sacking device between the middle elevator and the elevator at the other side.
- 5 3. In a portable grain cleaner, a supporting chassis, a suction screen machine including longitudinally extending aspirating and screening mechanism positioned forwardly on said chassis, an elevator and a conveyor arranged to receive
- 10 grain at the rear of the machine and convey it up and over the suction screen machine to deliver the grain at the front of the machine onto the aspirating and screening mechanism, a second elevator receiving grain from the suction
- 15 screen machine, a disk grain separator in communication with the second elevator, a smut treating machine above said disk grain separator, a third elevator receiving grain from the separator for delivery to the smut treating machine, an eccentric shaft for actuating the suction
- 20 screen machine extending transversely of the suction screen machine, a grain cleaner intermediate the length of said screens, means to drive the cleaner and eccentric shaft and drive means for the disk separator and smut treating machine actuated from said eccentric shaft.
- 25 4. In a portable grain cleaner, a supporting chassis, a suction screen machine including longitudinally extending aspirating and screening mechanism positioned forwardly on said chassis, a grain hopper, an elevator and a conveyor arranged to receive grain at the rear of the machine from the hopper and convey it up and over the suction screen machine to deliver the grain at the front end of the machine onto the aspirating and screening mechanism, a grain bin at the rear of the suction screen machine and in front of the elevator, a second elevator receiving grain from the grain bin, a disk separator receiving grain from the second elevator, a smut treating machine forwardly of the elevator and above said disk separator, a third elevator for delivering grain to the smut treating machine, means to drive said screens, separator, elevators and smut treating machine including an eccentric shaft, a frame on said chassis for supporting the several mechanisms, bearings for the eccentric shaft supported from the front of rear posts of the frame of the suction screen machine, a pair of vertically spaced blocks between the bearings and supporting posts and a tailings spout extending through the space between said blocks on one side.
